UNITED STATES PATENT OFFICE.

LEON SIMON, OF WEST HOBOKEN, NEW JERSEY.

DESIGN FOR A HUSK FOR LIGHTING FIXTURES.

Application filed September 17, 1924. Serial No. 10,808. Term of patent 7 years.

To all whom it may concern:

Be it known that I, LEON SIMON, a citizen of the United States, and a resident of West Hoboken, in the county of Hudson and State of New Jersey, have invented a certain new, original, and ornamental Design for a Husk for Lighting Fixtures, of which the following is a specification, reference being had to the accompanying drawing, forming a part hereof.

Fig. 1 is a top plan view of a husk for

lighting fixtures showing my new design which consists of a series of representations of draped hearts and a representation of a draped bell interposed between adjacent heart representations.

Fig. 2 is a side elevation of the husk showing my new design.

I claim the ornamental design for a husk for lighting fixtures, as shown and described.

LEON SIMON.
